GRINDING MILL INCLUDING VIBRATING FEED HAMMER

Merle Gordon Ellsworth, Bloomington, Ill.

Application August 4, 1955, Serial No. 526,496

4 Claims. (Cl. 241—222)

This invention relates generally to grinding mills and has to do more particularly with a novel mill for grinding granular materials, such as sand and gravel.

An object of the present invention is to provide a new and improved grinding mill.

Another object is to provide a new and improved grinding mill of relatively simple construction capable of grinding relatively coarse, hard material to a relatively fine size.

Another object is to provide a grinding mill having smooth surfaced grinding rolls but which is nevertheless capable of grinding relatively coarse, hard material to a relatively fine size.

Another object is to provide a grinding mill having a pair of cooperating rolls and means for preliminarily crushing against the rolls prior to its passage between the rolls the material to be ground and for forcibly feeding such material into the nip of the rolls.

Another object is to provide a grinding mill of the type having a pair of closely spaced, opposed rolls, wherein is provided a hammer positioned above the nip of the rolls and vibrated relatively to the rolls to crush the material against the rolls and thereby reduce the size of the particles to that which will be nipped by the rolls and to aid in feeding the material to the nip of the rolls.

Still another object is to provide a grinding mill having a pair of opposed, closely spaced grinding rolls wherein is provided novel mounting means for the rolls which is simple and inexpensive and whereby the spacing of the rolls may be quickly and easily effected.

Another object is to provide a simple, inexpensive but effective means for mounting the grinding rolls of a grinding mill whereby the rolls may be quickly and easily removed and replaced.

Another object is to provide a grinding mill having a simple and effective mechanism for preliminarily crushing particles of the material to be ground prior to its passage between the rolls.

Another object is to provide a grinding mill having a new and improved feed means for forcibly feeding to the nip of the rolls the material to be ground.

Other objects are to provide a grinding mill for grinding relatively hard granular material such as sand and gravel, which mill is simple in construction, relatively inexpensive to construct, effective in operation, capable of use over a long period without requiring repair or replacement of parts, and which requires a minimum of attention and care during operation.

Other objects and advantages of the invention will appear from the following description taken in connection with the appended drawings wherein:

Figure 1 is a side elevational view of a machine constructed in accordance with my invention;

Fig. 2 is a fragmentary view of the vibrating mechanism of the machine of Fig. 1 and illustrating somewhat diagrammatically the action of such mechanism;

Fig. 3 is a top plan view of the machine of Fig. 1;

Fig. 4 is a fragmentary, sectional view taken along

2

line 4—4 of Fig. 1 with the feed hopper removed to show the internal construction;

Fig. 5 is a fragmentary, sectional view taken along line 5—5 of Fig. 3; and

Fig. 6 is a fragmentary, sectional view taken along line 6—6 of Fig. 5.

For the purposes of illustrating my invention I have described the machine and its operations in connection with the grinding of gravel to produce fine sand. However, it is to be understood that the machine is not limited to this use and may be used for grinding any one of a number of materials of a granular nature to a greater degree of fineness. The machine is especially well adapted for grinding gravel to produce fine sand and by way of example, it may be used, for example, to grind gravel of a size of $\frac{3}{8}$ " to produce 50 mesh and 100 mesh sand.

It should also be understood that by reason of the adjustability of the spacing of the rolls the machine may be set to produce either a very fine sand or a somewhat coarser sand, depending upon the adjustment of the rolls. Owing to the grinding or crushing action of the rolls and also particularly to the crushing action afforded by the hammer (as hereinafter described), the material which passes through the rolls is not necessarily uniform in size but may range from the largest size particles which can pass between the rolls to very fine particles. Accordingly the product which is produced by the machine will consist of particles of various sizes. This product may and ordinarily will be screened in order to provide sand of different mesh for use in different applications. However, the construction of the machine is such that a relatively fine sand is produced even without screening.

For convenience in describing my invention I have designated herein that portion of the plane passing through the axes of the two rolls which lies between the opposing surfaces of the rolls as the "tangent zone." It will be understood of course that the rolls are not in actual contact but since they are relatively closely spaced it is believed that the zone of closest approach of the rolls may properly be designated as indicated. I have designated as the "approach zone" that space between the rolls which extends upwardly from the tangent zone to a plane tangent to the uppermost surfaces of the rolls.

The mill of my invention includes a casing 10 formed by a pair of spaced side walls 11 each having out-turned flanges 12 at their upper portions and spaced end walls 13 connecting the side walls at their end portions. The casing 10 is supported by any suitable means (not shown).

The top of the casing 10 is open to permit feeding of sand or gravel to the rolls (hereinafter described) and is open at the bottom to permit discharge of the ground material. If desired, the lower portion of the casing may be formed to provide a discharge hopper as shown particularly in Fig. 1 of the drawings, although this is not necessary.

Preferably I provide means for carrying away the ground material to a point of screening, storage or other disposition and for this purpose I provide a travelling conveyor 15 disposed below the bottom of the casing 10. However, the mill may discharge onto screening means or onto a storage area, or into a storage bin.

Mounted within the casing 10 is a pair of grinding rolls 20 which are positioned in opposition to rotate about parallel axes lying in a horizontal plane. The rolls 20 are so mounted that the distance between their surfaces at their point of closest approach is equal to the maximum size of the grains or particles of the material to be produced by grinding. Each of the rolls 20 preferably is of hollow construction and is formed by a cylindrical member 21 and a pair of end members 22 rigidly secured in and supporting the cylindrical member 21, as by welding. The roll 20 and particularly the cylindrical portion 21 there-

of is formed from a hard, long-wearing and shock-resistant material and for this purpose I prefer to use a suitable manganese steel although other suitable materials may be employed. The peripheral, grinding surfaces of the rolls preferably are smooth in order to insure fineness of the ground product.

The rolls 20 are of the same diameter and are so supported that they rotate about axes which are parallel and in the same horizontal plane. Each of the rolls 20 is secured on a mounting shaft 25 in a removable manner as by keys 26 cooperating with slots in the end members 22 and in the shaft 25. Each shaft 25 extends at both ends through openings 30 in the side walls 11 and is journaled in bearings 31. Each bearing 31 is of rectangular form and is mounted in a rectangular recess 32 in the outer face of the side wall 11 and in alignment with the corresponding opening 30. The bearing recess 32 is of such height as to snugly fit the bearing 31, but with sufficient clearance to permit sliding adjustment of the bearing 31 therein in a horizontal direction. On the other hand the bearing recess 32 is of slightly greater length than the bearing 31 so that the bearing may be adjusted horizontally in the opening. A shim 33 is provided which is inserted between the bearing and the corresponding end of the recess 32.

The foregoing arrangement permits the adjustment of the rolls in a direction toward and away from each other in order to accommodate for wear in the surfaces of the roll. When the rolls are new and are of full peripheral dimensions the shims 33 are disposed at the end of each recess 32 nearest to the other recess so that the axes of the rolls are at the greatest separation. As the surfaces of the rolls wear and the clearance between the points of closest approach of the rolls becomes greater and it is desired to move the rolls closer together so as to provide the desired clearance between the rolls, one of the shims 33 is removed from its position and inserted between the bearing and the other end of the bearing recess 32 thereby to adjust the corresponding roll to a position closer toward the other roll. As further wear occurs in the surfaces of the roll the aforementioned operation is performed on the other roll so as to adjust it in the frame to a position closest to the first roll. Thus two different adjustments are provided.

Preferably I provide one shim for each of the bearings as I have found that for most purposes this is sufficient. However, it will be understood that a plurality of thinner shims may be provided in each bearing recess thereby to provide a finer adjustment of the bearings in their recesses. Thus, where a plurality of such shims are provided the adjustment of each roll may be made in steps successively as the surfaces of the rolls are worn rather than in a single operation as where but a single shim is employed in each bearing recess.

The bearings at one side of the casing (right-hand side as viewed in Fig. 4) are retained in their respective recesses 32 by cover plates 35 suitably secured to the side member 11 as by screws 36. It should be explained at this point that the arrangement of the key and slot connections between the shaft 25 and rolls 20, and the removable bearing arrangement permits the rolls to be removed readily from the machine and replaced when this is desired, as when the surfaces become so worn that they are incapable of grinding the material to the desired degree of fineness.

While I have shown and described the preferred form of mounting arrangement for the rolls in order to provide the desired adjustment, it will be understood that other adjustable bearing means may be provided. The construction which I have shown and described is extremely simple and effective in operation and is not readily subject to mal-functioning from any cause and particularly the presence of sand and dust as is inevitable in a sand mill or other similar mill.

Means are provided for rotating the rolls in synchro-

nism and at the same surface speeds. To this end I provide driving means which preferably is an electric motor 40 suitably supported, as by a bracket 41 fixed to the casing 10. Fixed on the motor shaft is a driving gear 42 which meshes with a driven gear 43 secured as by a key 44 on the shaft 25 carrying the roll 20. A similar gear 46 is similarly secured to the other shaft 25 and meshes with the first gear 43 whereby it is driven by the latter. Thus it will be seen that upon energization of the motor 10 both of the gears 43 and 46 are rotated and the rolls correspondingly rotated. The gearing arrangement is such and the direction of rotation of the motor is such that the rolls are rotated in opposite directions with their peripheries moving downwardly at their opposed inner portions (as indicated by arrows in Fig. 5 of the drawings).

I provide means for crushing against the peripheries of the rolls prior to its passage through the rolls the material, such as gravel for example, being delivered to the approach zone. Such means also is so constructed as to force the material into the nip of the rolls. To this end I provide a hammer 50 which is suitably supported (by means hereinafter described) pivotally in a position between the rolls and above the tangent zone. The hammer is formed with a head 51 formed with striking faces 52 which are planar and which converge to a bottom edge. While the angle between the faces 52 may be varied somewhat I prefer to form the faces 52 so that they are at similar angles to a longitudinal medial plane 25 through the hammer 50 and which planes are at an angle of approximately 45 degrees.

The size and proportions of the hammer 50 and particularly the head 51 thereof may be varied somewhat but I prefer to provide a head generally similar in size and arrangement to that shown in Fig. 5. Accordingly I prefer to form and locate the head 51 so that when it is in its lowermost position the lower edge thereof is located above the tangent zone. I prefer to form the faces 52 of such length that they extend a distance of approximately one-third the distance from the tangent zone to a plane tangent to the top surfaces of the rolls. The hammer 50 preferably is of such width that it extends throughout the lengths of the rolls 20.

The hammer 50 is formed of suitable material, such as metal which provides adequate weight and strength and I prefer to form it of a material which is resistant to wear and abrasion and shock and which therefore does not require frequent replacement. To this end I form the hammer of manganese steel similar to the material from which the rolls are formed, although other suitable materials may be used.

While I have shown the hammer 50 as comprising an enlarged end portion and a reduced shank, it will be understood that the portion above the head may take other forms. However, the arrangement shown is preferred as such arrangement is deemed to be most effective for the purposes for which it is employed. For convenience in describing the invention I employ the term "head" to designate that portion of the hammer having the striking faces, that is, the faces adapted to crush the material between the hammer and the rolls.

The hammer 50 is supported for swinging movement between the rolls and for vertical reciprocation by a mechanism now to be described. The hammer 50 is formed with a bearing portion 53 at its upper end which is supported on a shaft 54 for pivotal movement on the shaft whereby the hammer is suspended pivotally by the shaft 54. The shaft 54 is secured in and carried by a pair of hanger bars 55 disposed at the sides of the machine respectively. Each hanger bar 55 is guided for vertical reciprocating movement by a pair of guide brackets 56, each rigidly secured as by bolts 57 extending through the flange 12 of the corresponding side portion 70 of the flange and provided with a groove 58 forming a

a way in which the corresponding end of the hanger bar 55 slides and is guided.

The hanger bars 55 and the members carried thereby are supported normally in a predetermined position by a pair of coil springs 60 interposed between the bottom of each hanger bar 55 and the top of the flange 11 whereby the hanger bars and connected elements are resiliently supported. The springs 60 thus serve to cushion the hanger bars 55 and connected members as the latter are vertically reciprocated and to aid in causing reciprocating or vibrating movement of these members. Movement of the hanger bars 55 and connected members is limited by bolts 61 extending through the flanges 12 and secured therein as by nuts 62. The bolts 61 extend upwardly through the springs 60 and through suitably positioned openings 63 in the hanger bars 55. Interposed between the heads of the bolts 61 and the top of the hanger bars are buffer springs 65 and washers 66, which buffer springs cushion the upward movement of the hanger bars 55 and connected elements and prevent the hanger bars from striking the heads of the bolts 61.

A shaft 70 is journaled in bearings 71 secured as by bolts 72 to the upper surfaces of the two hanger bars 55 respectively. Secured on the shaft 70 for rotation thereby are a pair of vibrator wheels 76 each of unbalanced construction and thereby adapted to cause vertical reciprocation or vibration of the hanger bars 55 when the wheels are rotated. The wheels 76 are so formed as to be unbalanced by weighting one portion of the periphery of each to a greater extent than the remaining portions. Preferably I accomplish this by forming the wheels of generally dished construction with a flange which has a weighting portion 77 extending inwardly therefrom toward the center of the wheel to a greater extent than the remainder of the flange. Preferably the weighting portion 77 is of segmental form as shown.

The vibrating shaft 70 is driven in any suitable manner and I prefer to provide a pulley 80 which is rotated by an endless belt 81 preferably of multiple construction trained about a drive pulley 82 driven by a motor 83. The drive is so constructed as to permit the vibratory movement of the shaft 70. Accordingly, the motor 83 preferably is mounted for slight vibration in order to allow for the vibration of the shaft 70, although in certain cases this is not necessary as the drive belt 81 will accommodate such vibratory movement. Therefore, I support the motor 83 on a plurality of springs 84 which are seated on a bracket 85 secured to a casing 10 and connected to the bracket 85 as by bolts 86.

The suspension bars and the members carried thereby are not restricted against vertical movement except as such movement is restrained somewhat by the springs, but are only prevented from moving laterally, and hence the rotation of the vibrator wheels causes the suspension bars and connected members to be vibrated vigorously as the vibrator wheels are rotated.

It will be seen that the shaft 54 from which the hammer 50 is suspended and the shaft 70 which carries the vibrator wheels are supported in such manner that they retain their relative positions when the suspension bar 55 is vibrated and both of the shafts are vibrated simultaneously and in unison.

The vibrating mechanism is driven from a separate source of power from that driving the grinding rolls, principally because it is preferable that the source of power for the vibrating mechanism permit the vibrating movement of the drive shaft 70 and the connected vibrating members. It is not necessary that the drive of the vibrating mechanism be synchronized with the drive of the rolls. In fact the rate of vibration of the hammer is not critical it being necessary only that the hammer be vibrated at a sufficient rate to provide the necessary momentum of the hammer to crush the particles of material. It is preferable that the vibration be sufficiently

rapid to provide such crushing action at a sufficient rate to operate the machine at the optimum capacity.

It is desirable to insure that the surfaces of the rolls are clean and do not have wet sand adhering thereto as they move toward the nip. Accordingly I prefer to provide a pair of scrapers 90 which are disposed in position to bear against the peripheries of the rolls at positions somewhat below and outwardly of the nip and preferably above the lowest points on the roll peripheries. However the exact location of the scrapers 90 is not critical, it being desirable merely that they remove the wet sand or other adherent material prior to the time the rolls approach the point at which material to be ground is delivered thereto. The scrapers 90 are supported in any suitable manner and preferably are secured at their ends to the sides 11 of the flange.

It will be understood that the gravel to be ground may be deposited onto the rolls in any suitable manner. However I prefer to provide a hopper 100 for guiding the material onto the rolls and into the approach zone between the rolls. The hopper 100 may take any suitable form and preferably includes side plates 101 and end plates 102, the hopper being suitably secured to the frame 10 in a suitable manner (not shown) so as to support it above the rolls. Means (not shown) may be provided for preventing gravel from falling onto the shaft 70 and the shaft 54 which means may take the form of a cover or gable roof (not shown) extending between the side plates 101 of the feed hopper and disposed over such shafts.

In the operation of my machine the motor 40 is suitably energized to rotate the rolls 20. At the same time the motor 83 is energized to rotate the shaft 70 carrying the vibrator wheels 76. As the latter are rotated they cause vibration of the shaft 70 on which they are carried by reason of the fact that they are eccentrically weighted and inherently tend to move the shaft 70 out of its normal position. Owing to the fact that the shaft 70 is constrained against movement, except vertical movement, the unbalanced condition of the wheels 76 affects only vertical vibration of the shaft 70. The shaft 70 being carried by the hanger bars 55 which are resiliently supported by the springs 60, the vertical vibratory movement of the shaft 70 is permitted and enhanced, with the result that the hangers 55, together with the connected members, are vibrated in a vertical direction. The springs 65 also serve to contribute to this vibratory action.

The vibratory movement of the hammer 50 causes it to vibrate vertically with respect to the surfaces of the rolls 20 facing the surfaces 52 of the hammer 50. Thus any gravel particles which fall into the space between the faces 52 and opposing peripheries of the rolls 20 are crushed between a face of the hammer 50 and the opposing roll 20. Since the hammer 50 is pivotally suspended it is vibrated laterally as well as vertically as a result of striking against the faces of the rolls 20 or against particles of gravel between the faces 52 and the rolls 20. This compound vertical and horizontal reciprocation results in a beating or hammering action whereby the hammer 50 crushes between its faces 52 and the opposed faces of the rolls 20 the larger sized particles of gravel. The smaller particles of gravel and the fragments of the larger particles which have been crushed and broken by the action of the hammer 50 fall into the nip of the rolls below the hammer 50 and are carried between the rolls. The larger of such particles are crushed between the rolls owing to the pressure of the rolls and the fragments of such particles together with the smaller particles pass between the rolls. The hammer 50 serves not only to hammer and crush between its surfaces and the opposing surfaces of the rolls the gravel which is in position to be so crushed but also serves to tamp and force feed into the nip of the rolls the material which is deposited into the space between the rolls above the nip.

Thus it will be seen that the vibrating action of the hammer 50 serves both to crush the larger particles of gravel to a size such that they will be accepted by the nip of the rolls but also it serves to force feed the material to the nip of the rolls so that should such material be of slightly too large a size to be freely accepted by the nip and tend to resist passage into the nip of the rolls, the material is nevertheless fed to the rolls by the forcible action of the hammer 50 and crushed between the rolls.

The material which passes between the rolls falls down onto the conveyor 50 and is carried to a point of storage or use or further processing. Thus, such material may be discharged to a storage pile or a storage bin or passed to screens to segregate different sizes of the sand or it may be carried to a point of use or shipment, as will be understood.

It will be seen from the foregoing that my invention provides a highly effective grinding mill for grinding relatively hard granular material such as gravel to produce much finer material such as sand. The machine is simple, compact and positive in operation. It is inexpensive to construct and capable of operation over a long period of use without requiring repair or replacement of the parts. However, should such replacement of parts become necessary, as for example replacement of the rolls, this can be effected very readily in view of the simple novel mounting arrangement of the rolls and such replacement can be effected rapidly and with a minimum of shut-down time.

The operation of the machine is such that relatively coarse gravel may be crushed to provide relatively fine sand by a single pass of the gravel through the machine. This is accomplished by the use of two cooperating smooth rolls and the crusher and feeder mechanism employed, namely the hammer and its mounting and actuating mechanism. Previously it was found necessary to use a corrugated roll and a smooth roll to preliminarily crush the material and it was therefore not possible to crush a relatively coarse material to form a relatively fine product in a single operation. After such relatively coarse material was passed through a corrugated and smooth roll and a relatively coarse product produced, the product after screening resulted in a considerable quantity of relatively coarse material. In accordance with my invention it is possible to crush material, for example of $\frac{3}{8}$ of an inch, to produce material not larger than 50 mesh and of which a considerable proportion is 100 mesh or finer.

I claim:

1. A grinding mill comprising a pair of grinding rolls, means mounting said rolls in opposed relation for rotation about parallel axes in a horizontal plane, means for rotating said rolls, and means for crushing against said rolls, material to be ground, prior to its passage past and between said rolls, including a hammer having a downwardly tapered head formed with planar striking faces opposite said rolls respectively and extending substantially throughout the lengths of said rolls, means pivotally supporting said hammer with the head thereof between said rolls above the tangent zone thereof for free lateral swinging movement, said supporting means

being mounted for resilient movement in a vertical direction only, and an eccentric flywheel rotatably mounted on said supporting means for vertically vibrating said supporting means and said hammer.

- 5   2. A grinding mill comprising a pair of grinding rolls, means mounting said rolls in opposed relation for rotation about parallel axes in a horizontal plane, means for rotating said rolls, and means for crushing against said rolls material to be ground prior to its passage past
10   and between said rolls including a hammer having a downwardly tapered head formed with striking faces lying in planes extending at an angle of not more than 45° to each other, means pivotally supporting said hammer with the head thereof between said rolls above the
15   tangent zone thereof for free lateral swinging movement, said supporting means being mounted for resilient movement in a vertical direction only, and an eccentric fly-wheel rotatably mounted on said supporting means for vertically vibrating said supporting means and said hammer.
20   3. A grinding mill comprising a pair of grinding rolls, means mounting said rolls in opposed relation for rotation about parallel axes in a horizontal plane and means for rotating said rolls, and means for crushing against said rolls material to be ground, prior to its passage past and between said rolls, including a hammer having a downwardly tapered head, a suspension bar, means resiliently supporting said bar, means pivotally suspending said hammer from said bar for free swinging movement of said head between said rolls and above the tangent zone thereof, means guiding said bar for vertical movement only, and means for vibrating said suspension bar.
25   4. A grinding mill comprising a pair of grinding rolls, means mounting said rolls in opposed relation for rotation about parallel axes in a horizontal plane, means for rotating said rolls, and means for crushing against said rolls material to be ground prior to its passage past and between said rolls, including a hammer having a
30   downwardly tapered head, a suspension bar, means resiliently supporting said bar, means pivotally suspending said hammer from said bar with said head between said rolls and above the tangent zone, means guiding said bar for vertical movement and means for vibrating said suspension bar.
